UNITED STATES PATENT OFFICE.

ARTHUR ALLEN FAIRCHILD, OF PHOENIX, ARIZONA.

FILING DEVICE.

1,236,415.

Specification of Letters Patent. Patented Aug. 14, 1917.

Application filed August 7, 1916. Serial No. 113,619.

To all whom it may concern:

Be it known that I, ARTHUR ALLEN FAIRCHILD, a citizen of the United States, residing at Phoenix, in the county of Maricopa and State of Arizona, have invented certain new and useful Improvements in Filing Devices; and I do declare the following to be a full, clear, and exact description of the invention, such as will enable others skilled in the art to which it appertains to make and use the same.

This invention relates to improvements in filing devices.

The object of the invention is to provide a simple and efficient device of this character so constructed as to render it impossible to surreptitiously remove an article filed thereon without the fact being disclosed on an inspection of the removed article.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a front elevation of the parts broken away and in section;

Fig. 2 is an end view with the movable member shown swung outward in dotted lines.

The device constituting this invention comprises a filing device or binder in the form of a U-shaped frame 1 having longitudinally extending sockets 2 at the free ends of the legs thereof to receive fastening elements for securing the frame in position on a support S. The leg 3 of this U-shaped frame is provided on its inner face with a plurality of longitudinally spaced sockets 4 which are preferably threaded and are designed to receive the threaded ends 5 of article receiving and supporting rods 6 any desired number of which may be employed, three being here shown. The other leg 7 of the U-shaped member is provided with transversely extending apertures 8 which are aligned with the sockets 4 in the leg 3 and through which the rods 6 are designed to pass. These rods 6 are preferably provided at their outer ends with kerfed heads 9 to facilitate their insertion and removal, the

apertures 8 having flared seats 10 on the outer face of the leg 7 to receive the heads 9 of the rods so that when in operative position, these heads will be arranged flush with the outer face of said leg.

The leg 7 has its outer face cut away for a portion of its length, the cut away portion terminating at its inner end beyond the innermost aperture 8 and is provided at said end with an obliquely disposed shoulder 11 extending from the front to the rear face of said leg and inclining downwardly from said front face to said rear face. This shoulder 11 is designed to form a stop for a pivoted cover member 12, here shown in the form of a strip pivotally connected at its inner end by a pintle 13 to the cut away portion of the leg 7 adjacent the inner end of said portion. This strip 12 has the terminal 75 of its inner end inclined to conform to the inclination of the shoulder 11, so that when the strip is swung into closed position, this inclined end will abut said shoulder and limit the closing movement of the strip 80 which, when so closed, has its outer face arranged flush with the outer face of the larger portion of leg 7 although it need not necessarily be so formed.

This aperture covering strip 12 is pivoted 85 to swing laterally from the front to the rear of leg 7 and is adapted to be held in closed position by a screw 14 carried by the strip 12 and designed to engage a socket 15 formed in the reduced portion of leg 7. The strip 90 12 and the reduced portion of leg 7 are provided with registering apertures 16 and 17 which are designed to receive the shackle of a padlock (not shown) whereby these parts are secured in locked position to prevent the unauthorized opening of the cover member 12.

In the use of this invention, when it is desired to file a document or other article on one of the rods 6, the padlock is disengaged 100 from the members 12 and 17 and the screw 14 is loosened to separate it from the socket 15. The member 12 may then be swung laterally into the position shown in Fig. 2 to permit withdrawal of one or all of the 105 rods 6 as may be desired and the articles to be inserted are strung on these rods and after being so mounted, the rods are replaced in the sockets 4 and the strip 12 swung back into closed position and secured 110 by the screw 14 and the padlock. It will be obvious that when the parts are so arranged

that no article can be removed from one of the rods 6 except it be torn therefrom and an inspection of the article would immediately disclose the fact that it had been removed in this manner. It is of course understood that articles may be removed by an authorized person having the key to the padlock without tearing the article.

I claim:

- 10 1. A device of the class described comprising a pair of side bars connected at one end, one of said side bars having sockets in its inner face and the other having apertures extending transversely therethrough, article receiving rods extending through the apertured bar with one end engaging the sockets of the other bar, an aperture covering member pivotally mounted on the outer face of said apertured bar and means for holding said member in closed position covering the outer ends of said rods to prevent surreptitious removal of the rods.
- 15 2. A device of the class described comprising a unitary U-shaped frame, one leg

of which has longitudinally spaced sockets 25 in its inner face, the other leg having apertures extending transversely therethrough and aligned with said sockets, the apertured portion of said leg having its outer face cut away, an obliquely disposed shoulder at the 30 inner end of said cut away portion, a cover strip pivotally mounted on the outer face of said cut away portion with its inner end inclined to correspond with the inclination of 35 said shoulder and adapted to abut said shoulder when closed, its closing movement being limited thereby, means for holding said strip in closed position, and means for connecting the free ends of said legs to a support.

In testimony whereof I have hereunto set my hand in the presence of two subscribing witnesses:

ARTHUR ALLEN FAIRCHILD.
